(57) CLAIM

The ornamental design for child's kart as shown.

DESCRIPTION

FIG. 1 is a front perspective view of child's kart of the present invention;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines in the drawings depict portions of the child's kart that forms no part of the claimed design.
